T. J. Baldwin. Sheet. 2 Sheets.
Ruling Mach.

No 12,730. Patented Apr 17, 1855.

I. J. Baldwin. Sheets 2 of Sheets.
Ruling Mach.

No 12,730. Patented April 17, 1855.

UNITED STATES PATENT OFFICE.

T. J. BALDWIN, OF BRIDGEPORT, CONNECTICUT.

PAPER-RULING MACHINE.

Specification of Letters Patent No. 12,736, dated April 17, 1855.

To all whom it may concern:

Be it known that L. T. J. BALDWIN, of Bridgeport, in the county of Fairfield and State of Connecticut, have invented a new and Improved Paper-Ruling Machine; and I do hereby declare that the following is a full, clear, and exact description of the same, reference being had to the annexed drawings, making a part of this specification, in which—

Figure 1, is a plan or top view of my improved machine. Fig. 2, is a longitudinal vertical section of do, x , x , Fig. 1, showing the plane of section. Fig. 3, is a section of the fast and loose pulleys at the end of the large drum of the endless apron; y , y , Fig. 1, showing the plane of section. Fig. 4, is a section of the working parts of my improvement, taken at the line z , z , Fig. 1.

Similar letters of reference indicate corresponding parts in the several figures.

This invention relates to a new and improved paper ruling machine and consists in the peculiar means employed for elevating or lifting the pens from the sheets of paper at proper intervals, so that the required blanks or spaces may be left on the sheets.

To enable others skilled in the art to make and use my invention, I will proceed to describe its construction and operation.

A represents the frame of the machine of rectangular form, and constructed in the usual manner.

B represents an endless apron which works over drums or rollers C, D, one C, at the front and the other D, at the back end of the frame A, as shown in Fig. 2.

E, is a roller at the back end of the frame A, and F is a roller at the front end directly over the roller C, and G, is a roller at the upper end of uprights (a) (a) at the front end of the frame A. Around the three rollers E, F, G, cords or strings (b) pass, portions of which between the two rollers E, F, are in contact with the endless apron B, as clearly shown in Fig. 2.

H, Fig. 2 is a shaft, at the lower part of the frame A, said shaft having pulleys I, J, upon it. A belt (b') passes around the pulley I, and one end of the roller C, and a belt (c) passes around the pulley J, and a pulley K on a drum L, over which the endless apron B, passes, see Figs. 1 and 2.

M is a pulley attached to the inner surface of one of the sides of the frame A and a belt

(d) passes around the pulley M and the roller C, see Figs. 1 and 2.

N is a shaft on the upper part of the frame A, said shaft has a pulley O at one end, which pulley rests or bears upon the pulley M, see Fig. 4. The pulley O, has a recess (e) cut in its edge or periphery said recess being of curved form and corresponding inversely to a segment of the pulley M. On the shaft N, directly over the endless apron B, there is a pulley D', which has a pendent (f) attached to it, see Figs. 1 and 2, and adjoining the pulley O, on the same shaft N, there is a cam Q, see Fig. 1, and dotted lines in Figs. 2 and 4. There is also a stop (g) attached to the shaft N, and adjoining the cam Q. This stop is shown by dotted lines in Figs. 2 and 4.

On the end of the shaft (h) of the drum L, there are two pulleys K, R. The pulley K is fast to the shaft and has been previously referred to, but the pulley R is a loose pulley and has a hollow hub or boss (i) at its center. The fast pulley K also has a hub or boss (j) which encompasses the shaft (h) and the hub or boss (j) passes through the hub or boss (i) of the loose pulley and has a disk (k) screwed to it, see Fig. 3. The outer edge of the hub or boss (i) passes into a collar (l) which encompasses the hub or boss (j) and a spiral spring (m) is placed around the collar (l) within the hub or boss (i). S, is a spring catch which passes into the collar (l) and through the hub or boss (i), a hole being made in the collar and hub or boss (i) to receive the spring catch, see Figs. 3 and 4.

T, Figs. 1, 2 and 4, is a lever having its fulcrum at (n) on the frame A. The outer end of the lever T rests or bears upon the periphery of the cam Q, as shown clearly in Figs. 2 and 4.

U is a lever having its fulcrum at (p), the inner end of this lever rests upon a projection (r) on the side of the loose pulley R, see Fig. 4. The loose pulley R is provided with projections V, V, on its periphery.

W is the pen beam to which the pens X are attached, the lower ends of the pens rest upon the endless apron B. The pen beam works loosely in bearings (s) (s) on the frame A.

The hubs or bosses (i), (j), collar (l) and spring (m) form a spring friction clutch and connect at the proper time, the loose

pulley R with the fast pulley K as will presently be shown.

Operation: Power being applied to the rollers C, the endless apron B, is moved over the rollers C, L, D, and the sheets of paper (a') are fed in between the apron B, and the cords (b). The front edges of the sheets strike the pendant (f) and rotate the shaft N, a trifle so as to throw the recess (e) in the pulley O, off of the pulley M and as the peripheries of the two pulleys are then in contact the shaft N rotates and the prominent parts of the cam Q raises the lever T and the lever T in raising throws the spring catch S up out of the collar (l) and hub or boss (i), and the spring (m) consequently forces the loose pulley R against the fast pulley K sufficiently tight to cause the loose pulley to rotate and the projections V, V, on the loose pulley, tilt or raise the pen beam W and the pens are raised from the paper. The projections V may be of any length and placed on the pulley at proper points so as to act properly or at the desired time upon the pen beam. The pulley R may make one revolution during the passage of each sheet of paper underneath the pens and the pulley O, also makes one revolution in the same time, the recess (e) fitting over the pulley M and preventing any casual movement of the

shaft N. The stop (g) and lever U, serve to stop the motion of the shaft N at the termination of every revolution.

Having thus described my invention, what I claim as new and desire to secure by Letters Patent, is,

Lifting the pens X, from the sheets of paper (a') at the proper intervals by means of the mechanism herein shown and described, viz: having the front edges of the sheets (a'), as they move along on the endless apron B, strike against a pendant (f) attached to a pulley D', on a transverse shaft N, on the frame A, said shaft being provided with a pulley O at one end having a recess or groove (e), cut in its periphery and a cam Q, the pulley O, working on bearings on a pulley M, underneath it, said pulley M, being driven by a belt (d), from the driving shaft C. The cam Q, operating a lever T, by which the spring clutch is allowed to act and connect the pulleys K, R, at one end of the drum L, the projections V, on the lower pulley R, raising the pen stock so as to leave the blanks or spaces at the desired parts of the sheets, as herein set forth.

T. J. BALDWIN.
